UNITED STATES PATENT OFFICE

2,195,902

FLUID IMPELLING OR IMPELLED DEVICE

Albert R. Pezzillo, Philadelphia, Pa.

Application July 26, 1939, Serial No. 286,593

7 Claims. (Cl. 103—90)

One of the main objects of my present invention is to devise a novel construction and arrangement of a fluid impelling or impelled device, which, if desired, can be connected directly into a pipe line to form a part thereof and an axial line of flow, and which may operate as a fluid meter.

The fact that my pump must start against a head, and that during idle periods there may be an accumulation of sediment or any other foreign matter that may cause a seizure, it is advisable to use a motor of high starting torque.

A motor of high starting torque would mean a single or split phase type. In a motor of this type, it is necessary, in order to obtain high starting torque, to use a centrifugal starting switch. It is impractical to use a centrifugal starting switch in my device as it would, in my application, be in the fluid.

By using an electrical starting relay, which is installed and operates exterior of my device, I have been able to eliminate the centrifugal starting switch heretofore deemed necessary, and still use a split phase type of motor, and have a high starting torque.

A further object of the invention is to devise a novel housing with a novel construction and arrangement of stator windings and rotor, and novel means having high electrical resistance, to isolate the stator windings from the fluid and dampen any electrical interference or hum and in such a manner as to act as a sound deadener.

A further object of the invention is to introduce into the fluid passing through the pipe line, other fluid which passes through the tubular shaft of the rotor.

A further object of the invention is to extend the intake end, or delivery end or both ends of the rotor blade into a stationary casing portion where it will have a working fit so that, in the case of a fluid pump, the initial flow of the fluid can be started and maintained against a head pressure of the fluid, and if desired, compressed before delivery to the pipe line at the delivery end of the pump.

A further object of the invention is to so construct and arrange the bearings that they are lubricated by fluid and are elongated to ensure long life without inspection or repair.

With the above and other objects in view as will hereinafter more clearly appear, my invention comprehends a novel fluid impelling or impelled device.

It further comprehends a novel fluid impeller, wherein an impeller carried by a tubular rotor

has one or more portions of its blade mounted to have a working fit in stationary portions at the intake or discharge ends, or at both intake and discharge ends of the housing with provision for a high starting torque on the motor so that the fluid can be initially impelled under a head pressure and a continuous flow of the fluid maintained.

Other novel features of construction and advantage will hereinafter more clearly appear in the detailed description and the appended claims.

For the purpose of illustrating the invention, I have shown in the accompanying drawing typical embodiments of it, which, in practice, will give satisfactory and reliable results. It is, however, to be understood that the various instrumentalities of which my invention consists can be variously arranged and organized and my invention is not limited to the exact arrangement and organization of these instrumentalities as herein set forth.

Figure 1 is a sectional elevation of a fluid impelling or impelled device, embodying my invention.

Figure 2 is an end elevation partly broken away of Figure 1.

Figure 3 is a side elevation partly in section, of another embodiment of my invention.

Figure 4 is a sectional view, the section being taken substantially on line 4—4 of Figure 1.

Similar numerals indicate corresponding parts.

Referring to the drawing:

1 designates the housing or casing consisting of end members 2 and 3, recessed to receive a shell 4, the parts being secured in assembled position by rods 5.

The end members 2 and 3 have integral with them the spiders 6 provided with hubs 7 which have self lubricated bearings 8, such as for example graphite bearings.

A tubular or hollow rotor 9 has as seen in Figure 1, a conical bore 10 which increases in diameter towards the outlet end. An impeller 11 in the form of a helical blade has the outer periphery of its blade fixed in any desired manner, for example by welding to the inner wall of the bore of the rotor, and is also fixed to a shaft 12, preferably tubular, and mounted in the bearings 8 in axial alignment with a pipe line 13. The impeller blade at the fluid intake end has a portion 14 of substantially uniform diameter which extends with close tolerance into the cylindrical bore 15 of a cylinder 16 extending inwardly from the end housing member 2.

The end housing member 3 also has an in-

wardly extending cylindrical portion 17, and if desired, the impeller blade 11 has a desired number of turns 18 of substantially uniform diameter extending into said portion 17.

5 The outer chamber of the housing which contains the stator windings 19 is sealed from the fluid in the rotor by a cylinder 20, opposite ends of which are sealed by gaskets 21 connected with the end housing members.

10 Flanged pipe fittings 22 secured in any desired fluid tight manner to the end housing members are connected in the pipe line 13.

It will be understood that the sealing cylinder 20 has a high electrical resistance and isolates the stator windings from the rotor and the fluid passing therethrough. It is of a material which will act as a sound deadener and which will reduce to a minimum, any hum that might occur with an A. C. current if such current is 20 used.

The motor is provided with a relay 23 and with an overhead cutout 24 of any conventional types.

In order to make provision for mixing or commingling different types of fluids, the tubular 25 rotor shaft 12 may be connected by a pressure packed slip coupling 25 with a pipe 26 leading from a source of fluid supply separate from that of the pipe line 13, and preferably provided with a check valve 27.

30 If my device is to be used as a flow meter, the supply current would be considerably reduced and the input wires connected to an ammeter, properly calibrated, so that, when fluid is forced through the rotor, the latter will revolve and the 35 current will indicate on the ammeter the volume and rate of flow. The pressure created by the impeller at its discharge end causes a Venturi action at the discharge end of the tubular shaft, entraining fluid through the hollow shaft to mix

40 with the fluid being pumped. When the pump stops the check valve 27 prevents reverse flow through the hollow shaft. The helical impeller blade has an extension of the blade extending into a stationary bore at one or both ends of the blade 45 a substantial distance. This distance is determined by the pitch of the blade, or the use of a straight helical blade, or of a diverging blade, and the pressure which it is desired to create.

50 In numerous experiments which I have made I have found that if the blade diverges within the rotor, the extension of the blade into the stationary bore can be of less length than if a helical blade is used which is of uniform diameter throughout its length.

55 In the form shown in Figure 3, the construction is the same as that of Figure 1, except that the rotor instead of having a conical bore has a straight bore 28, and the portion 29 of the impeller blade within the rotor is of substantially 60 uniform diameter.

If the bore of the rotor increases from its intake end to its discharge end, with the portion of the impeller blade within the rotor correspondingly increasing in diameter, a greater pressure is 65 created on the fluid being impelled with increased efficiency over a blade of uniform diameter.

The stationary bore for the discharge end of the impeller blade, in many cases, is not necessary. When employed, it provides an increased 70 pressure on the fluid.

If it is desired to operate my device as a flow meter, the impelling blade is driven by the fluid passing through the device. This causes the blade to revolve in a reverse direction from that 75 in which it operated as a pump. The electrical

resistance builds up, which can be calibrated and indicated on a meter.

Having thus described my invention, what I claim as new and desire to secure by Letters Patents is:

1. In a fluid impelling or impelled device, a housing having a fluid inlet and a fluid outlet and a stationary bore at its intake end, a tubular rotor in the housing, and a helical blade fixed in the rotor and having at its intake end a helical extension of the blade projecting into said stationary bore a substantial distance and having a working fit therein. 5

10 2. In a fluid impelling or impelled device, a housing having a fluid inlet, a fluid outlet and a stationary bore at its intake end, a tubular rotor in the housing and a helical blade fixed within the rotor and diverging in the direction of flow and having at its intake end a helical extension of the blade projecting into said stationary bore a 20 substantial distance and having a working fit therein.

25 3. In a fluid impelling or impelled device, a housing having an inlet, an outlet, a stationary bore at the inlet and a stationary bore at the 25 outlet, a tubular rotor within the housing, and a helical blade fixed within the rotor and having extensions of the blade projecting into said stationary bores a substantial distance and having a working fit therein and shaped to create a desired 30 pressure on the fluid being pumped.

35 4. In a fluid impelling or impelled device, a housing having an inlet, an outlet and a stationary bore at the outlet end, a tubular rotor in the housing, and a helical blade within the rotor 35 and having an extension of the blade projecting into said stationary bore a substantial distance and having a working fit therein and shaped to create a desired pressure on the fluid pumped.

40 5. In a fluid impelling or impelled device, a housing comprising end members forming an inlet and an outlet, and a cylinder between said end members and sealed therewith, said end member at the intake end having a stationary bore, a tubular rotor in the housing, and a helical 45 blade fixed in the rotor and having an extension of the blade projecting into said stationary bore a substantial distance and having a working fit therein and shaped to create a desired pressure on the fluid pumped. 50

45 6. In a fluid impelling or impelled device, a housing comprising end members forming an inlet and an outlet, and a casing sealed between said members, said members forming spiders with bearing receiving hubs, bearings in said hubs, the 55 end members at the intake end having a stationary bore, a tubular rotor within the housing, a helical blade fixed within the rotor and having an extension of the blade projecting into said bore a substantial distance and having a working fit 60 therein and shaped to create a desired pressure on the fluid pumped, and a shaft fixed to said blade and mounted in said bearings.

55 7. In a fluid impelling or impelled device, a housing having an inlet, an outlet and a stationary bore at its intake end, a rotor in the housing, a helical blade fixed in the housing and having an extension of the blade projecting into said stationary bore and shaped to create a desired pressure, a tubular shaft fixed to said blade and 70 open at its discharge end to the fluid pumped, and a conduit leading from a separate source of fluid supply having a check valve, and communicating with the inlet end of said tubular shaft.
